UNITED STATES PATENT OFFICE

GEORGE E. NAGEL, OF COLUMBUS, OHIO

BURIAL VAULT

Application filed March 4, 1932. Serial No. 596,840.

My invention relates to a burial vault.

The essential objects of my invention are to provide, in a manner as hereinafter set forth, a concrete burial vault formed of a series of separate units capable of being readily assembled when occasion requires and with the units comparatively light in weight to enable conveniently handling them when assembling the vault; having the inner face of each unit provided with a series of panels to reduce the weight thereof and the amount of material required less than would be the case with respect to a full thickness unit of equal dimensions; reinforcing the units to provide for superior strength; forming one of the units with knockout portions for drainage when desired; having a bottom, a top, a pair of sides and a pair of end units capable of being assembled together in a waterproof vault and with each panel having its inner face formed with transverse and lengthwise extending, spaced, intersecting ribs; having the transverse ribs of each unit reinforced to increase the strength of the latter; and to attain these ends in an unusually strong, durable, compact, thoroughly efficient and comparatively inexpensive structure.

To the above ends essentially, and others which may hereinafter appear, the invention consists of such parts and such combination of parts which fall within the scope of the invention as claimed.

In the drawings:

Figure 1 is a perspective view of a burial vault in accordance with my invention, and with the top unit raised and spaced from the vault body.

Figure 2 is a sectional plan of the vault body.

Figure 3 is a longitudinal view of the vault.

Figure 4 is a transverse sectional view of the vault.

Figure 5 is a fragmentary view in sectional plan of a unit.

The vault includes a top unit 1 providing the lid or closure, a lower unit 2 forming the bottom, a pair of side units 3, 4 providing the side walls and a pair of end units 5,

6 forming the end walls of the vault. The units 3, 4, 5 and 6 are superimposed upon unit 2. The unit 1 is seated upon the units 3, 4, 5 and 6. Each unit is constructed from reinforced concrete. The units 3, 4 are of like construction, but oppositely disposed with respect to each other. The units 5, 6 are of like construction, but oppositely disposed with respect to each other. The units 1, 2, 3 and 4 are of rectangular contour. The units 1, 2 are of equal length. The units 3 and 4 are of less length and width than that of units 1, 2. The units 4, 5 are rectangular and the width thereof corresponds to that of the units 1, 2. When the vault is set up the height of units 5, 6 corresponds to that of units 3, 4 and the latter are arranged between and abut units 5, 6.

The unit 1 is formed on its inner face with a set of spaced, parallel lengthwise extending ribs 7 of a length greater than that of the width thereof. The inner face of unit 1 is also formed with a set of spaced parallel transverse ribs 8 merging into the ribs 7. The outer ribs 7 of the set of lengthwise extending ribs are spaced from the side and end edges of unit 1. The outer ribs 8 of the set of transversely extending ribs are spaced from the end edges of unit 1. Each rib is of tapered cross section. The inner face of unit 1 is recessed to provide panels 9 and the ribs 7 and 8 form continuations of the walls of the recesses. The outer sides of the outer ribs 7 and outer ribs 8 are of less height than the inner sides thereof as indicated at 10. The side and end marginal portions of the inner face of unit 1 exteriorly of and in proximity to the outer ribs 7 and 8 are formed with lengthwise and transverse grooves 11, 12. The outer sides 10 of the outer ribs 7 and 8 provide shoulders, abutments or stops for the side and end units. Each side edge of unit 1 in proximity to the end edges thereof is formed with pockets 13 to receive a removable lowering means for unit 1.

The upper or inner face and side edges of unit 2, are constructed in a manner similar to that of unit 1, with this exception,

unit 2 is not provided with the grooves 11, 12, but is formed with reduced parts to provide knockout portions 14 for drainage not formed in unit 1. The lengthwise ribs, 5 transverse ribs, panels and pockets of unit 2 are indicated at 15, 16, 17 and 18 respectively. The reduced knockout portions 14 are arranged centrally of the panels 17. The ribs on unit 2 are of tapered cross section.

10 The unit 3, as well as the unit 4 has the inner face thereof constructed in a manner similar to that of unit 1, but with this exception, the outer ribs have their outer sides flush with the edges of the unit. The lengthwise ribs, transverse ribs and panels of each side unit are indicated at 18', 19 and 20 respectively. The ribs of the units 3, 4 other than the outer of such ribs are of tapered cross section. The outer of said ribs have 20 beveled inner sides. The edge of each unit 3 or 4 which is to oppose unit 1 is formed with a lengthwise extending groove 21 for registration with a groove 11 to form a channel of circular cross section for the reception 25 of a sealing compound 22.

The unit 5 as well as the unit 6 has the inner face thereof formed with horizontally and transversely extending ribs 23, 24 respectively and recessed to provide panels 25. 30 The ribs 23, 24 form continuations of the walls of the recesses. The outer of the ribs 23 and of the ribs 24 have their outer sides flush with the edges of the unit. The ribs of units 5 and 6 other than the outer of said ribs are of tapered cross section. The outer of said ribs having beveled inner sides. That edge of unit 5 or unit 6 which is to oppose unit 1 is formed with a groove 26 which registers with a groove 12 to form a channel of circular cross section to receive a sealing means 26'.

The grooves 11 and 12 merge into each other. The grooves 21 and 26 merge into each other. The units 3, 4, 5 and 6 have 45 coacting grooves to provide channels 22' to receive sealing means 23' for sealing the corners of the vault and connecting such units together.

Each transverse rib of each unit has embedded therein a reinforcing rod 27 extending through a plurality of spaced chairs 28, each consisting of a flat body having concave edges 29 to provide points 30 at the corners thereof. The points at the outer 50 corners of each chair 28 are flush with the periphery at the point of joinder of the sides with the front of the rib. Each chair 28 has an axial opening 31 for the passage of the reinforcing rod.

60 Each unit between the transverse ribs of the latter has its body reinforced by spaced opposed parallel bars 32 extending transversely thereof. Each bar 32 passes through a set of spaced chairs 33 of the same construction as the chairs 28. Each chair 33

has its points flush with the outer face of a unit and with a panel.

The length of each reinforcing bar is less than the transverse length of that unit in which it is embedded and has its ends spaced 70 from edges of the unit adjacent such ends.

What I claim is:—

1. A burial vault comprising, a lower unit, a pair of upstanding end units for seating upon the end marginal portions of the upper face of the lower unit, a pair of upstanding side units for seating upon the side marginal portions of the lower unit and interposed between and abutting said end units, a top unit for seating on the side and end units, each of said units having its inner face formed with spaced recesses to provide panels, and each of said units having its inner face provided with spaced, intersecting ribs extending at right angles to each other to form continuations of the walls of the recesses, certain of said ribs being disposed transversely of said units, a set of spaced apertured chairs embedded in each transverse rib and each chair having tapered parts providing corner points, each chair of each set having a plurality of the points of each chair being flush with one face of the rib in which the chair is embedded, spaced sets of spaced apertured chairs embedded in each unit and each chair having tapered parts providing corner points flush with the inner and outer faces of the unit, and a reinforcing bar extending through the apertures of and common to the chairs of a set. 100

2. A burial vault comprising, a lower unit, a pair of upstanding end units for seating upon the end marginal portions of the upper face of the lower unit, a pair of upstanding side units for seating upon the side marginal portions of the lower unit and interposed between and abutting said end units, a top unit for seating on the side and end units, each of said units having its inner face formed with spaced recesses to provide panels, each of said units having its inner face provided with spaced, intersecting ribs extending at right angles to each other to form continuations of the walls of the recesses, the outer of the ribs on the top and bottom units abutting the outer ribs on the inner faces of the side and end units, certain of said ribs being disposed transversely of said units, a set of spaced apertured chairs embedded in each transverse rib and each chair having tapered parts providing corner points, each chair of each set having a plurality of the points of each chair being flush with one face of the rib in which the chair is embedded, spaced sets of spaced apertured chairs embedded in each unit and each chair having tapered parts providing corner points flush with the inner and outer faces of the unit, and a reinforcing bar extending 110

120

through the apertures of and common to the chairs of a set.

3. In a burial vault formed of a series of concrete assembly units, each unit having its inner face provided with two sets of spaced ribs, the ribs of one set extending at right angles to and intersecting the ribs of the other set, a set of spaced centrally apertured chairs embedded in each of the ribs of one set, each chair formed with tapered portions to provide corner points, a plurality of the points of each chair flush with one face of the rib in which the chair is embedded, and a reinforcing bar extending through the apertures of the chairs of each set.

4. In a burial vault formed of a series of concrete assembly units, each unit having its inner face provided with two sets of spaced ribs, the ribs of one set extending at right angles to and intersecting the ribs of the other set, a set of spaced centrally apertured chairs embedded in each rib of one set and each chair having tapered parts providing points, a plurality of the points of each chair being flush with one face of the rib in which the chair is embedded, spaced sets of spaced centrally apertured chairs embedded in each unit and each chair having tapered parts providing points flush with the inner and the outer faces of a unit, and a reinforcing bar extending through the apertures of the chairs of each set.

5. A burial vault comprising, a lower unit, a pair of upstanding end units for seating upon the end marginal portions of the upper face of the lower unit, a pair of upstanding side units for seating upon the side marginal portions of the lower unit and interposed between and abutting said end units, a top unit for seating on the side and end units, each of said units having its in-

ner face formed with spaced recesses to provide panels, each of said units having its inner face provided with spaced, intersecting ribs extending at right angles to each other to form continuations of the walls of the recesses, the outer of the ribs on the top and bottom units abutting the outer ribs on the inner faces of the side and end units, the said ribs being spaced inwardly of edges of the units, certain of said ribs being disposed transversely of said units, a set of spaced apertured chairs embedded in each transverse rib and each chair having tapered parts providing corner points, each chair of each set having a plurality of the points of each chair being flush with one face of the rib in which the chair is embedded, spaced sets of spaced apertured chairs embedded in each unit and each chair having tapered parts providing corner points flush with the inner and outer faces of the unit, and a reinforcing bar extending through the apertures of and common to the chairs of a set, and said top, side and end units formed with grooves, the grooves of the side and end units registering with the grooves in the top unit to provide channels for the reception of a sealing unit.

6. In a burial vault, a series of assembly units, each formed with a plurality of panels on its inner face, an inner and an outer set of spaced centrally apertured chairs embedded in each unit, the chairs of the outer set being formed with spaced points flush with the inner and outer faces of the unit, the chairs of the inner set being formed with spaced points flush with the inner face of the unit, and a reinforcing bar extending through the apertures of the chairs of each set.
